No. 634,621.

Patented Oct. 10, 1899.

S. H. JONES.

KNIFE.

(Application filed July 14, 1899.)

(No Model.)

UNITED STATES PATENT OFFICE.

SAMUEL H. JONES, OF SCRANTON, PENNSYLVANIA, ASSIGNOR OF TWO-THIRDS TO WADE M. FINN, OF SAME PLACE, AND JOHN B. SHANNON, OF CARBONDALE, PENNSYLVANIA.

KNIFE.

SPECIFICATION forming part of Letters Patent No. 634,621, dated October 10, 1899.

Application filed July 14, 1899. Serial No. 723,843. (No model.)

To all whom it may concern:

Be it known that I, SAMUEL H. JONES, a citizen of the United States, residing at Scranton, in the county of Lackawanna and State of Pennsylvania, have invented certain new and useful Improvements in Knives, of which the following is a specification.

My invention relates to an improved form of knife intended for general household use, the novel and useful features of which are pointed out in the following specification and claims.

In the accompanying drawings, which illustrate my invention, Figure 1 is a side perspective view of my improved knife, and Fig. 2 is a cross-section on the line 2 2 of Fig. 1.

Referring to the drawings, A indicates the knife-blade, and B the handle. The handle may be of any desired form; but it is preferably of the shape shown in the drawings, and it is secured to the blade in any suitable manner.

The blade A consists of a plate of sheet-steel, comparatively wide, having cutting edges 1 and 2 on its opposite sides and a longitudinal opening 3 in the center, which separates the main part of the blade into two narrow cutting strips or blades 4 and 5. The side walls 6 and 7 of the opening converge gradually from the butt-end 8 toward the forward end 9, the opening being inclined to the body of the blade, as shown, so that the strip 4 is broader at the butt-end than at the forward end, while the strip 5 is wider at the forward end than at the butt-end. The forward end 9 of the blade as a whole is inclined away from the cutting edge 2 and toward the cutting edge 1, the former edge curving gradually outward toward the point 10, as shown, and the latter having an inclined portion 11, which extends from about the end of the strip 4 to the point 10.

The cutting edge 2 is designed particularly for cutting raw meat. In cutting steaks, for instance, from a section of beef the skilled operator always draws the knife toward him. It is desirable, therefore, to have the forward portion of the cutting edge 2 curved backward, as shown at 12, and as the wear on this

edge occurs principally at the forward part

of the knife the inclination of the tapering opening leaves the forward end of the tapering strip 5 wide enough to allow for considerable wear. It is also found advantageous for this purpose to have a narrow stiff blade. 55 By my improvements a narrow blade or cutting-strip 5 is provided, and it is rendered rigid by its connection at the forward end with the strip 4.

The cutting edge 1 is designed for use in cutting bread, cake, pastry, &c. This edge is suitable for the back-and-forth motion generally employed in cutting bread, the inclined part 11 cutting the crust on the side away from the operator as the knife is drawn toward him, making a clean cut and the rear part of the blade cutting the crust upon the near side. In the use of this side of the knife the cutting is mainly effected upon the forward thrust, so that the rear part of the strip 70 4 wears faster than the forward part, and hence the rear part of the strip is made wider than the forward part.

In dividing pastry the knife is drawn toward the operator and the inclined edge 11 75 cuts through the body of the material, the point 10 making a clean cut through the lower crust to the bottom of the pan or dish.

The blade A is about the width of the ordinary bread-knife, so that it is naturally 80 guided in a straight line through any stiff thick material, such as bread, which does not fall away from the blade as rapidly as the knife is drawn through it, while the strip 5 is as narrow as is found necessary for cutting 85 raw meats which naturally separate and fall down after each cut. The opening in the center of the blade lightens and cheapens the construction, and the tapering walls of the opening are also convenient for the purpose of 90 tightening and loosening nuts of various sizes, the knife thus serving as a wrench. When not in use, the knife may be suspended upon the wall by passing the blade over a nail or hook, so that the latter will project through 95 the opening. In addition to the special uses for which the knife is designed it is obvious that it may be employed for many other purposes.

Having described my invention, what I 100

claim, and desire to secure by Letters Patent of the United States, is—

1. In a knife for household use, a knife-blade having its forward end inclined to the main or body portion, cutting edges extending throughout the length of the blade on either side and meeting at the point, the center of the blade being removed so as to leave narrow cutting-strips 4 and 5 in the main portion of the blade, substantially as described.

2. In a knife for household use, a knife-blade having cutting edges extending throughout the length of the blade on either side, and a longitudinal opening in the body of the blade, said opening being inclined and dividing the blade into two tapering strips 4 and 5, substantially as described.

3. In a knife for household use, a knife-blade having its forward end inclined to the main or body portion, cutting edges extending

throughout the length of the blade on either side and meeting at the point, and a longitudinal tapering opening 3 in the body of the blade.

4. In a knife for household use, a knife-blade having its forward end inclined to the body, a cutting edge 1 having an inclined part 11 and a cutting edge 2 curving gradually rearward at the forward end of the blade and meeting the cutting edge 1 at the point, and a longitudinal opening in the body of the blade dividing it into two comparatively narrow cutting-strips 4 and 5, substantially as described.

In testimony whereof I affix my signature in presence of two witnesses.

SAMUEL H. JONES.
